UNITED STATES PATENT OFFICE.

BERNARD GILPIN, OF COULSDON, ENGLAND.

TOBACCO-PIPE.

1,162,476.

Specification of Letters Patent. Patented Nov. 30, 1915.

Application filed September 28, 1915. Serial No. 53,114.

To all whom it may concern:

Be it known that I, BERNARD GILPIN, a subject of His Majesty the King of England, residing at Coulsdon, in the county of

5 Surrey, Kingdom of England, have invented certain new and useful Improvements in Tobacco-Pipes, of which the following is a specification.

This invention relates to improvements in 10 the construction of tobacco pipes of the kind in which it has been proposed to incline the mouthpiece proper upwardly in relation to the stem so as to dispose the free end of the bore of said mouthpiece above 15 and away from the tongue and thus prevent saliva flowing into the pipe. In pipes having straight mouthpieces it has been proposed to form shoulders thereon at a considerable distance away from the free end 20 of the mouthpiece to position said end beyond the tip of the tongue, and to make said mouthpiece of tapered shape in vertical section from the shoulders to the free end.

25 According to the present invention a pipe is formed or fitted with a mouthpiece which is formed with opposite upper and lower shoulders disposed at a distance of at least three-quarters of an inch from the free end 30 of the mouthpiece or of the bore of same, is inclined upwardly in relation to its stem from said shoulders and is of tapered and convex shape in vertical section from the shoulders to said free end, as hereinafter 35 described with reference to the accompanying drawing and claimed.

The drawing illustrates two enlarged vertical sectional views of the improved mouthpiece. The stem *a* of the mouthpiece may 40 be formed straight as in Figure 1 or curved as in Fig. 2 or both, and the end *b* of said stem, or the mouthpiece proper, which is adapted to be held within the mouth behind the teeth, is disposed at an angle in relation 45 to said stem and directed upwardly and

rearwardly. This arrangement disposes the end *c* of the bore of the mouthpiece above the tongue and adjacent to the roof of the mouth.

The upper and lower shoulders *d* on the 50 mouthpiece for engagement behind the teeth are formed thereon at a distance of at least three-quarters of an inch from the extreme end of same, as above mentioned, so that the end *c* of the bore is held well back in the 55 mouth and away from the tip of the tongue.

The upturned mouthpiece is of such shape that it is tapered and convex on a vertical section from the shoulders *d* to its free end, as shown, so that it cannot be gripped in the 60 teeth between said shoulders and said end.

The mouthpiece may be made of any suitable material and be fitted to a new or an existing pipe having a straight or curved stem. The stem *a* of the mouthpiece may be 65 short or long as desired and according to requirements.

What I claim as new and desire to secure by Letters Patent of the United States is:—

A mouth piece for tobacco pipes, comprising an integral body portion and an end portion forming a mouth piece of olive shape which is bent upwardly at an angle from the body portion, the mouth piece being thicker in cross section than the thickness in cross section of the body portion, the outer end of the mouth piece at the point of juncture with the body portion forming a shoulder on the upper and lower sides of the stem, the body portion and the stem having an opening for the passage of the smoke, that portion of the opening extending through the mouth piece being upwardly inclined and passing through the upper surface of the mouth piece in advance of the 80 rear end of the latter.

In testimony whereof I have hereunto signed this specification.

BERNARD GILPIN.
